ATTORNEY

UNITED STATES PATENT OFFICE.

ALFRED V. BODINE, OF BRIDGEPORT, CONNECTICUT, ASSIGNOR TO DICTAPHONE CORPORATION, OF BRIDGEPORT, CONNECTICUT, A CORPORATION OF NEW YORK.

SOUND MODIFIER.

Application filed May 24, 1924. Serial No. 715,593.

This invention relates to sound-modifiers for sound producing devices, such as telephones and loud speakers; for sound reproducing devices, such as phonographs; and for sound conveying devices, such as speaking tubes.

In the accompanying drawings, in which the invention is shown as applied to the sound-box of a dictation machine of the 10 transcribing type:

Figure 1 is an elevation and shows one embodiment of the present invention.

Fig. 2 is a sectional view of the sound-modifier shown in Fig. 1, on line 2—2 Fig. 15 1, looking from the right.

Fig. 3 is a similar sectional view taken on the line 2—2 of Fig. 1, looking from the left.

Fig. 4 is a top plan view of the modifier shown in Fig. 1.

Fig. 5 is a vertical section taken on the line 5—5 of Fig. 4.

Fig. 6 is a horizontal section taken on the line 6—6 of Fig. 1.

Fig. 7 is a disassembled perspective view 25 of the parts of the sound modifier shown in the other figures.

As shown in the accompanying drawings, the carriage 10 of a transcribing dictation machine is provided with an opening 11 into 30 which fits the sound-box 12 carrying a diaphragm 13 having a suitable connection 14 to a stylus adapted to engage a phonograph record. The vibrations of the diaphragm produced by the phonograph records, 35 produces in the sound-box 12, a succession of sounds substantially the same as those which were recorded by the phonograph record. These sounds are transmitted through a nozzle 15 provided on the sound-box 12 and 40 ultimately reach the operator's ears through hearing devices, comprising sound-conveying tubes and ear-engaging parts.

The volume of the sound produced by the diaphragm 13 and transmitted to the operator with different records varies in intensity and volume in accordance with the intensity or the volume of the sound originally recorded. It is, therefore, advantageous to provide a modifier to vary the volume or intensity of the sound, so that the actual sound received by the operator may be substantially uniform for different records, by merely adjusting the modifier.

It has been found, in providing modifying

devices, that when the sound-passage is 55 merely reduced in area to reduce the volume, the sound is stifled or muffled, and otherwise changed in characteristics. However, this muffled effect is not produced when the sound is modified by allowing a portion of it 60 to escape. Yet, when the sound is thus modified solely by allowing a portion of it to escape, the resulting sound has a nasal characteristic.

I have found that by combining means for 65 modifying the sound by changing the cross-section of the sound-passage and means for modifying the sound by varying the opening of an escape-passage, the disadvantages of both methods of sound modification are 70 practically eliminated.

To this end, I provide upon the nozzle 15, a housing 16 having a socket 17 to receive the nozzle 15 and provide the housing with a sound-transmitting passage 18 and a sound 75 escape-passage 19. The sound-transmitting passage 18 is provided with a nozzle 20 adapted to receive a tube 21 for conveying the sound to the ears of the user; while the sound-escape passage leads directly to the 80 atmosphere. The openings 18 and 19 are directly opposite each other and at right angles to these is a passage 22 leading to the socket 17 which fits upon the nozzle 15.

The passage of sound between the opening 22 and the openings 18 and 19 is controlled by means of a controller or gate 23 which is preferably cylindrical in form and which is rotatably mounted in a hole 24 provided in the housing 16 to receive it. The 85 gate 23 is provided with a finger-piece 25 by means of which it may be rotated to control the position of a sound-passage 26 provided therein. The vane 27 directly opposite the passage 26 is equal to about one-half the 90 diameter of the gate 23 and since the passages 18 and 19 are exactly opposite each other, the vane 27 will close one passage as it opens the other. For instance, as seen in Fig. 3, the passage 26 through the gate 100 23 allows communication between the escape-passage 19 and the sound-passage 22, while the vane 27 closes the sound-transmitting passage 18 and would prevent all sound from being transmitted through the passage 18 105 were it not for the fact that the vane 27 is provided with a circumferential bleed-groove 28 which allows a slight amount of

sound to pass and reach the operator's ears. Thus, when the gate 23 is in the position shown in Fig. 3, a minimum of sound is transmitted and a maximum is allowed to escape.

When, however, the gate is rotated to the position shown in Fig. 2, sound is allowed to pass through the transmitting passage 18 at about one-half the full volume. The other 10 half of the sound is also allowed to escape through the passage 19 as shown by the tail-less arrows in Fig. 2.

When the gate 23 is rotated to the position shown in dotted lines in Fig. 2, a maximum 15 volume of the sound is transmitted through the passage 18 to the operator's ears, while only a slight amount is allowed to escape through the bleed-groove 28. In practice, the operator starts to adjust the modifier 20 with the gate in the position shown in Fig. 2, and then gradually rotates the gate by means of the finger-piece 25 until the volume of the sound is satisfactory for the best work.

25 The upper portion of the housing 16 is provided with a threaded aperture 29 adapted to receive a screw 30 having a stud 31 at its end, which is adapted to engage a segmental groove 32 provided in the gate 23. 30 As shown in Fig. 3, the bottom of the segmental groove 32 engages the stud 31 of the screw 30 which limits the movement of the gate between its extreme open and closed 35 positions. In addition to this, the stud 31 serves to retain the gate in position in the hole 24 as shown in Fig. 5.

In assembling the device, it is merely necessary to place the gate 23 in the hole 24 and adjust the screw 30 into position. To 40 take up any looseness which may exist between the wall of the segmental groove 32 and the stud 31, and for the purpose of holding the gate 23 in adjusted position, a spring 33 is interposed between the end 34 of the 45 gate 23 and the wall 35 at the end of the opening 24. This spring 33 is held in proper position by a stud 36 provided on the end of the gate 23. By pressing the wall of the groove 32 against the stud 31, the spring 33 50 produces sufficient friction to hold the gate 23 in adjusted position against accidental displacement.

The housing 16 of the modifier is secured to the nozzle 15 of the sound-box by means 55 of a screw 37 threaded therein and engaging the nozzle 15.

While the present invention has been shown as applied to the sound-box of a dictation machine, it is also applicable to any 60 other device in which sound is produced or transmitted. For instance, it may be used in a loud-speaker for wired or wireless telephony; in the tone-arm or at the sound-box of an ordinary phonograph, instead of employing 65 shutters and sound-baffling devices

at the outlet of the horn; and in the sound-conduit of speaking tubes.

Variations and modifications may be made within the scope of this invention and portions of the improvements may be used without others.

Having now described the invention, what is claimed as new, and for which it is desired to obtain Letters Patent, is:

1. A sound modifier comprising sound-transmitting means; sound-escape means having free access to the atmosphere; and an adjustable vane means for coordinately opening the sound-transmitting means and closing the sound-escape means at a single 80 operation, and means for holding said adjustable vane in adjusted position intermediate its limits of movement.

2. A sound modifier comprising a housing; sound-transmitting means in the housing; sound-escape means in the housing, opposite the sound-transmitting means; and a rotatable gate having a single vane adapted to simultaneously control the sound-escape means and the sound-transmitting 90 means.

3. A sound modifier comprising a housing; a rotatable gate mounted within the housing; and means mounted within the housing adapted to engage a segmental groove provided in the gate and limit the movement of the gate by engagement with the bottom thereof.

4. In a dictation machine, a sound-box; sound-conveying means on the sound-box; and means mounted on the sound-box and located between the sound-box and the first-named means for allowing portion of the sound produced by the sound-box to escape before it reaches the sound-conveying means. 105

5. In a dictation machine, a sound-box; sound-conveying means on the sound-box; and means mounted on the sound-box for simultaneously controlling the passage of sound to the sound-conveying means and controlling the escape of the sound before it reaches the sound-conveying means. 110

6. In a dictation machine, a sound-box; sound-conveying means on the sound-box; and manually operable means mounted on the sound-box and located between the sound-box and the first-named means for allowing a portion of the sound produced by the sound-box to escape before it reaches the sound-conveying means. 115

7. In a dictation machine, a sound-box; sound-conveying means on the sound-box; and manually operable means mounted on the sound-box for simultaneously controlling the passage of sound to the sound-conveying means and controlling the escape of the sound before it reaches the sound-conveying means. 125

8. In a sound-modifying device, sound-transmitting means; sound-escape means; 130

and adjustable means for controlling the sound-escape means and the sound-transmitting means, said means being shaped to always allow passage of some sound through the sound-escape means.

9. In a sound-modifying device, sound-transmitting means; sound-escape means; and adjustable means for controlling the sound-escape means and the sound-transmitting means, said means being shaped to always allow passage of some sound through the sound-transmitting means.

10. A sound modifier comprising a support; sound-transmitting means in the support; sound-escape means in the support; a vane adapted to either close or open sound-escape means and simultaneously either open or close the sound-transmitting means; and a by-pass between the vane and the support

to permit passage of some sound through said sound-escape means when the vane is in maximum closed position with relation to the sound-escape means.

11. A sound modifier comprising a support; sound-transmitting means in the support; sound-escape means in the support; a vane adapted to either close or open the sound-escape means and simultaneously either open or close the sound-transmitting means; and a by-pass between the vane and the support to permit passage of some sound 25 through said sound-transmitting means when the vane is in maximum closed position with relation to the sound-escape means.

Signed at Bridgeport, in the county of Fairfield, and State of Connecticut, this 22nd day of May, 1924.

ALFRED V. BODINE.
